UNITED STATES PATENT OFFICE.

FRED C. WENDELL, DECEASED, BY THERESA S. WENDELL, ADMINISTRATRIX, OF
NEW YORK, N. Y.

IRONING-MACHINE.

1,118,712.

Specification of Letters Patent. Patented Nov. 24, 1914.

Original application filed February 1, 1913, Serial No. 745,701. Divided and this application filed April 12, 1913. Serial No. 760,689.

To all whom it may concern:

Be it known that FRED C. WENDELL, late a citizen of the United States, deceased, did invent certain new and useful Improvements in Ironing-Machines, of which the following is a specification.

This is a divisional application of the pending patent application filed February 1, 1913, Serial No. 745,701.

10 This invention relates to ironing machines of the type wherein a heated drum combined with pressure rollers and an apron are used for feeding moist fabrics around the drum and pressing them around its periphery, and thereby the ironing is accomplished.

15 The principal object of the invention is to provide an efficient and improved ironing machine.

Another object is to provide a machine 20 having improved means for ironing both sides of the fabrics when fed therethrough in a single operation.

A still further object is to provide improved means for maintaining a uniform 25 pressure at each end of the pressure rollers, and to maintain said pressure uniform at all times.

According to the invention, the usual 30 heated drum is provided with pressure rollers for ironing one side of the fabrics fed thereto, and a secondary similar drum for ironing the opposite side is mounted to rotate oppositely immediately below the former. Endless aprons coöperate with said 35 drums in contact with their peripheries.

Said aprons are combined with guide-rolls adjacent said drums whereby portions of the aprons coöperate with said rolls to reverse the fabric as it leaves the first drum 40 and present it to the periphery of the second drum for ironing its opposite side. The fabric is conveyed from the latter drum by its coöoperating apron to a delivery table.

Air cylinders are provided for each of the 45 bearings of said pressure rollers, and pistons therein are connected to said bearings, whereby the pressure of compressed air is applied upon said pressure rollers to exert a uniform pressure thereon against the periphery of said drum and the intervening fabrics. The air pressure is reversed and applied to the opposite side of the piston 50 for maintaining the rollers away from said drum when the machine is not in use.

Other objects and advantages will herein- 55 after appear.

In the accompanying drawings, Figure 1 is a general side elevation of the ironing machine. Fig. 2 is an enlarged view, partly in section, showing the air pressure device 60 for the pressure-rolls. Fig. 3 is a sectional elevation of the ironing machine. Fig. 4 is a front elevation, on an enlarged scale, of the automatic apron controlling mechanism for the ironing machine. Fig. 5 is a 65 side view of Fig. 4. Fig. 6 is a plan view of Fig. 4.

A hollow steel cylinder, or ironing drum 1 is rotatably mounted on the machine frame 2, by its hollow journals 3 running in bearings 4 secured to said frame, and a similar oppositely revolving secondary drum 5 is rotatably mounted immediately below the drum 1, by its journal 6 running in bearings 7 of said frame. Said drums are disposed 70 horizontally in the machine and parallel to each other, and steam is admitted within the drums through the hollow journals 3 and 6, whereby the drum peripheries are heated and rendered suitable for ironing. 80

An endless apron 8 coöperating with the drum 1 is in contact with its periphery at the lower side thereof, and extends therefrom over a drive-roll 9, diagonally downwardly from said roll toward the drum 5, 85 under an idle-roll 10, over a guide roll 11, around idlers 12, 13, under a slack roll 14, over an idler 15, and back to the drum. With the drum 5 coöperates an endless apron 16 which encircles it in contact with its periphery, and extends therefrom over an idle roll 17, from there over and around a drive roll 18, thence over an idler 19, under a slack roll 20, around idlers 21, 22, over a guide-roll 23, under an idler 24, diagonally 90 upward and around an idler 25, to an idler 26, and back to the drum. All of said rolls are provided with suitable bearings secured to the machine frame 2. The portion of the apron 16 from roll 25 to roll 26 is approximately parallel to the portion of the apron 8 from roll 9 to roll 10, and at the roll 9 the apron 16 is in contact with the apron 8, so that both of said aprons run in contact with each other toward the drum 5, due to the 95 aprons running in opposite directions. 100

Pressure rollers 28, preferably five in number, coöperate with the periphery of

drum 1 upon the upper side thereof for pressing the fabrics thereagainst, and a feed-apron 29, provided at the feeding side 30 of the machine, slopes diagonally upward toward the first of said pressure rollers 28^a, and conveys the fabric thereto. Said feed-apron passes around a board 31, the sharp edge 32 of which is disposed between the pressure roller 28^a and the periphery 10 of the drum 1, and it extends around and is driven by a roll 33, mounted in a bearing 34 upon the machine frame 2.

The driving mechanism of the machine comprises a drive-shaft 37 which carries a 15 pinion 38 meshing with a gear 39 keyed to the journal 6 whereby the drum 5 is driven in a clockwise direction as viewed in the drawing. Gear 39 meshes with a gear 40 on the roll 17, and a sprocket 20 41 on said roll is connected by means of chain 42 to a sprocket 43 upon the roll 18 which drives the apron 16. The gear 39 meshing with a similar gear 44, keyed to the journal 3, rotates the drum 1 25 in an opposite direction to the drum 5 and at the same speed. Gear 44 meshes with a gear 45 fixed to the drive roll 9, which drives the apron 8, and a sprocket 46 keyed to said roll drives all of the pressure rollers 30 28 by means of sprockets 47 and sprocket chains 48. A sprocket 49 on drive shaft 37 and a chain 50 therefor drive a sprocket 51 fixed to roll 33 whereby the feed apron is driven.

35 The moist fabrics to be ironed are kept in a long receptacle 52 provided at the feed side of the machine. When ironing, the operator spreads the fabric flat and places it upon the feed apron 29 against the table 40 53 fitted in the machine frame 2. Said apron then feeds the fabric under a straightening roll 54, held in yokes 55 secured to frame 2, and into the machine between the first pressure roller 28^a and the periphery of the drum. It is then carried 45 around the drum 1, in contact with its hot surface, under the successive pressure rollers 28 and between the endless apron 8 and the drum, during which course the fabric 50 is thoroughly ironed on one side. From the drum 1 the fabric is carried over the roll 9 and between the portions 8^a and 16^a of the aprons 8 and 16 to the secondary drum 5. In its passage over the roll 9 and through 55 said portions of the aprons the fabric is reversed, so that its opposite side is presented to the hot surface of the drum 5, and being held pressingly thereto by the apron 16 running in contact therewith the fabric is thoroughly ironed upon its opposite side while carried around this drum. Upon leaving the drum 5, the fabric is conveyed by the upwardly inclined portion 16^b 60 of the apron 16 over the roll 18, where it is deposited in finished condition upon a deliv-

ery table 56 fixed to brackets 57 extending from the frame 2 opposite the feed side 30 of the machine.

A doffer-roller 58, held in arms 59 mounted on the roll 17, has a gear 60 in mesh with a gear 6 key to said roll whereby it is driven in contact with the drum 5 to prevent accidental climbing or sticking of fabrics upon its periphery. Springs 62 fixed to frame 2 at 63 draw the arms 59 to cause the rotating 70 doffer-roller to bear pressingly against the drum. A similar doffer-roller 64, having a gear 65 in mesh with a gear 66 upon the roll 9, coöperates with the drum 1 above said roll and serves a similar purpose therat.

The slack rolls 14 and 20 having bearings 67 slidable on guide-rods 68 fixed to frame 2 weigh down upon the aprons 8 and 16, whereby they are maintained taut while the machine is in operation and the required 80 pressure of said aprons against the drums 1 and 5 is effected. As it is desirable for the preservation of the aprons to maintain them slackened and out of contact with the hot drum while the machine is not in use, gears 69 are fixed to said slack rolls and are in mesh with racks 70 fixed to frame 2, so that when said rolls are rotated, by means of hand-wheels 71 fixed thereto, they may be raised and the aprons properly slackened; 90 said rolls being maintained raised by any suitable means, such as by tying a counter-weight to the rims of the hand wheels.

The aprons 8 and 16, which are about as wide as the drums have a tendency to shift 100 off laterally to the right or left, and this shifting tendency, characteristic in machines of this kind, occurs to such an extent as to interfere seriously with the working of the machine, and sometimes destroys the aprons. To obviate such undue amount of lateral shifting automatic mechanism is provided for each apron, shown in Figs. 1, 4, 5, and 6. Said mechanism includes the apron-control 105 guide-roll 11 or 23. The end of said roll remote from said mechanism is pivoted in a bearing 72 of the frame 2, and its opposite journal 73 is held in a bearing box 74, of the mechanism, slidable parallelly to the apron in a channeled portion 75 of a base-plate 115 76 fixed to the frame 2, so that by sliding said box the roll may be swung angularly to the apron about the bearing 72. Within the box 74 are rotatably-mounted rollers 77, and the journal 73 having a grooved portion 78 120 is seated and runs upon said rollers, which constitute a bearing for said roll.

Dogs 79 and 80 depend from a hub 81 which is pivoted eccentrically to the extremity of the journal 73 by means of the stud 125 82. A lever 83 has a rock-shaft 84 forming part thereof fulcrumed at 85 on the box 74, and its opposite arm 86 extending from said shaft loops around so that its extremity 87 engages the forked end 88 of an arm 89 ex- 130

tending from the hub 81, whereby the rising of said lever will cause the dog 80 to engage a coöperating toothed portion 90 provided on the base-plate 76, while the falling 5 of the lever will cause the dog 79 to engage a similar coöperating portion 91 thereof.

The lever 83 is provided with a thickened cylindrical portion 92, made preferably of wood and of a required weight, which continually 10 rests upon the edge 93 of the apron; a weight 94 adjustable along an extension 83^a of the lever serving to counterweigh the end 92 to an extent, if found necessary. Assuming that the apron in its shifting tendency 15 shifts in the direction of the mechanism, the lever 83 will rise thereby and the dog 80 be caused to engage its toothed portion 90, so that for every revolution made by the roll its eccentricity with the hub 81 will cause the box 74 to slide and said roll to swing angularly for a distance of one tooth 90^a to the left of a perpendicular to the apron, as viewed in the drawing. This angular swinging will continue until a maximum 20 point is reached when said angularity will cause a recession of the apron and it will shift oppositely and cause a gradual falling of the lever 83. For an interval, therefore, the apron runs true, during which 25 time the dogs 79, 80 are disposed in the inactive position shown in Fig. 4. As the apron-shifting in the opposite direction however continues, the lever 83 falls further, and the dog 79 is thereby caused to engage 30 the portion 91, whereby the opposite effect takes place and the roll is swung to the right of a perpendicular to the apron, which again restores the true running of the apron. Such deliberate predetermined shifting of 35 the apron in both directions is in this way continually effected by the said controlling mechanism, which is automatically operated by the apron itself in its shifting tendency, and the excessive lateral shifting of the 40 apron is thereby prevented.

The pressure rollers 28 are mounted in bearings 95, Fig. 2, which are slidable in guiding-ways 96 of guides 97, forming part of the machine frame 2, that extend radially 45 from the center of drum 1. Air cylinders 98 are secured to said guides, at each end of the pressure-roller, by means of a flange 99 of the cylinder being bolted thereto, and pistons 100 coöperating with the cylinders have their piston-rods 101 secured to the 50 bearings 95, by means of heads 102 of said rods fitting in jaws 103 on said bearings. A plug 104 threading into the top of the cylinder serves as a cylinder-head, and offers 55 a convenient means of assembling during construction.

When the machine is in operation during ironing, compressed air is admitted into the cylinder 98 through the port 105 from an 60 air compressor, and a required pressure is

maintained above the piston 100 and transmitted to roller 28, whereby suitable pressure of said rollers against the intervening fabrics and the periphery of the drum 1 is effected. With this utilization of air for 65 said pressure rollers absolutely uniform pressure is applied at each end of the rollers at all times, and even if an immoderately thick fabric be forced to pass under said rollers the pressure would still remain uniform, and such maintenance of uniform pressure is conducive to the production of even and uniformly fine grade of ironing work. When the machine is not in use the air above each piston 100 is allowed to 70 exhaust and compressed air is admitted below each of said pistons through ports 106, so that the pistons are shifted to the opposite ends of cylinders 98 and the rollers 28 are thus lifted and maintained away from the 75 drum 1 to preserve their felt peripheries from injury by its heat. The chains 48 have considerable slack to compensate for the increased distance between the centers of their sprockets when the rollers are lifted. While 80 the machine is in operation said slack is taken up by rollers 107, Fig. 1, carried on links 108 being drawn against said chains by springs 109 fixed to the frame 2.

Variations may be resorted to within the 85 scope of the invention, and portions of the improvements may be used without others.

Having thus described the invention, I claim:

1. An ironing machine having the combination of a revoluble heated drum, a plurality of pressure rollers coöperating therewith for ironing the goods, pneumatic mechanism at the ends of said rollers adaptable to bear against said ends and exert uniform pressure of the peripheries of said rollers upon the goods, and means to reverse the operation of said mechanism to move and maintain said pressure rollers away from 100 said drum.

2. An ironing machine having the combination of a revoluble heated drum, a plurality of pressure rollers coöperating with the periphery of said drum, said rollers being shiftable toward and away from said drum, air cylinders, pistons therein, piston-rods connecting said rollers with said pistons, and means to admit air of uniform pressure to said pistons to cause said rollers to exert uniform pressure of their peripheries upon the goods.

3. An ironing machine having the combination of a revoluble heated drum, a plurality of pressure rollers coöperating with the periphery of said drum, pneumatic mechanism at the ends of said rollers adaptable to bear against said ends and exert uniform pressure of said rollers against said drum, and guides for said mechanism disposed radially to said drum; said mechanism includ- 125

ing air cylinders fixed to said guides, pistons therein, piston-rods connecting said rollers with said pistons, means to admit air of uniform pressure to said pistons to exert uniform pressure upon the goods, and means for reversing the air pressure within said cylinders to move and maintain said rollers away from said drum.

4. An ironing machine having the combination of a revoluble heated drum, a plurality of pressure rollers coöperating with its periphery for ironing the goods, and mechanism at the ends of said rollers including fixed air cylinders, pistons therein, piston-rods connecting said rollers with said pistons, means to admit air of uniform pressure to said pistons to exert uniform pressure of the peripheries of said rollers upon the goods, and means for reversing the air pressure within said cylinders to move and maintain said rollers away from said drum.

5. An ironing machine having the combination of a revoluble drum, a plurality of pressure rollers coöperating with the periphery of said drum for ironing the goods, pneumatic mechanism at the ends of each of said rollers adaptable to bear thereagainst and exert uniform pressure of the peripheries of said rollers upon the goods, and means to move and maintain said rollers away from said drum.

6. An ironing machine having the combination of a revoluble heated drum, a plu-

rality of pressure rollers coöperating with its periphery for ironing the goods, cylinders 35 for said rollers, pistons coöperating with said cylinders, and means to admit fluid of uniform pressure to said pistons to exert uniform pressure of the roller peripheries upon the goods.

7. An ironing machine having the combination of a revoluble heated drum, a plurality of pressure rollers coöperating therewith for ironing the goods, and pneumatic mechanism at the ends of said rollers adaptable 45 to bear against said ends and exert uniform pressure of the peripheries of said rollers upon the goods.

8. An ironing machine having the combination of a revoluble heated drum, a plurality of pressure rollers coöperating therewith for ironing the goods, and mechanism adaptable to apply fluid pressure upon each of said rollers to exert uniform pressure of the peripheries of said rollers upon the 55 goods.

Signed at the city of New York, in the county of New York, and State of New York, this 5th day of April, A. D. 1913.
